Attorney

UNITED STATES PATENT OFFICE.

HARRY K. SWEENEY, OF ALCOVA, WYOMING.

CONNECTION FOR CULVERTS.

1,408,485.

Specification of Letters Patent.

Patented Mar. 7, 1922.

Application filed March 24, 1921. Serial No. 455,345.

To all whom it may concern:

Be it known that HARRY K. SWEENEY, a citizen of the United States, residing at Alcova, in the county of Natrona and State 5 of Wyoming, has invented certain new and useful Improvements in Connections for Culverts, of which the following is a specification.

This invention has reference to improvements in connections for culverts, drains 10 and the like, having particular reference to that form of culvert such as described and claimed in my United States Patent No. 1197966.

15 The invention has for an object to provide a simple but effectual form of connection for joining the opposite sides of a sectional plastic or other form of culvert or drain, whereby said sections will be securely held in their 20 connected or joined relation and will be held against any attempt at lateral movement with relation to each other, such as would tend to detract from the practicability and objects sought to be accomplished by the 25 culvert.

It is also an object of my invention to provide a connection of the character mentioned which is so formed as will permit of ready 30 and quick engagement as between the several parts thereof, in order that the sections of a culvert or a drain to be joined thereby may be as quickly connected.

Other objects will be in part obvious and in part pointed out hereinafter:

35 In the drawings:

Figure 1 is a fragmentary perspective of a section of a culvert provided with my improved connection;

40 Figure 2 is a similar view of the opposite section of the culvert;

Figure 3 is a vertical fragmentary section in detail through portions of the culvert sections showing the inter-engaged elements of the connection; and,

45 Figure 4 is a fragmentary detail in perspective of the improved connection.

Having more particular reference to the drawings, in connection with which like characters of reference will designate corresponding parts throughout, my invention 50 may be applied to that type of sectional culvert or drain as shown in the Figures 1 and 2, whose sections are designated by the numerals 1 and 2 and are semi-circular in 55 shape. These sections, obviously, when arranged in adjacent relation, will provide the

usual form of drain, and to render fluid-type connection between these two sections, I preferably form longitudinally extending tongues on the lower marginal portions of 60 the section 1, and indicated at 3, these tongues being adapted to be received in correspondingly disposed grooves 4 formed in the adjacent portions of the section 2, thus affording an inter-engaging connection as 65 between said portions of the sections 1 and 2.

As means for effectually connecting the sections 1 and 2 of the culvert, I arrange in equi-distant relation in the grooves 4 formed in these portions of the section 2 adjacent 70 the tongues 3 of the sections 1, a plurality of upstanding eyelets 5, which, as will be noted, are provided with shank portions which are embedded in the plastic composition 75 of the section 2.

Engaged in the free portions of the section 1 adjacent to the tongues 3 formed thereon and arranged to correspond to the positioning of the eyelet 5, are a plurality of engaging members, which I shall designate by the numeral 6. These engaging members are provided with shank portions which are embedded in the plastic composition 80 of which the section 2 is formed, and have their free portions bent laterally in 85 substantially elbow like or U-shaped fashion, thus providing engaged portions operable with the hooks such as designated by the numeral 7. The free ends of these hook portions 7 are bent downwardly at substantially 90 right angles in proximity to the point of bending of the hooks from their respective shank portions and, as will be appreciated, afford, in this way, a positive and dependable form of connection or engaging 95 means, which, when the upper or free portions thereof are passed through the corresponding eyelets 5 of the section 1 of the culvert, will afford means for engaging said section 1 with the section 2, and in addition 100 to serving as means for preventing relative vertical movement between these two sections, will also prevent material lateral movement as between the two sections 1 and 2. The latter is accomplished by the piv- 105

otating of the inwardly swinging lip or stop 8 on the free end of each of the hook portions 7, which lips, as hereinbefore stated, have their free ends normally abutting or engaging to the opposite side of the U- 110 shaped hook portion in proximity to the point of bending of the portions 7 from the

shanks of the hooks whereby to prevent outward swinging movement of the same. It of course will be understood that the lips 8 are of such width as will permit their passage 5 through the openings in the eyelets 5. Thus, when the pivoted lips 8 are passed through their respective eyelets 5, the lower or free portions thereof will swing downwardly into engagement with the lower side of the substantially 10 U-shaped hooked portions 7, as clearly shown in the Figure 4, and by consequence, lateral disengagement of said hooked portions from their respective eyelets 5 will be prevented, since, as above 15 stated, the pivoted lips 8 are only permitted inwardly swinging movement and any attempt at outwardly swinging movement of the same will be prevented by reason of their engagement with the lower side of the 20 U-shaped hooked portion 7.

From the foregoing it will be understood that I have provided a simple but effectual form of connection for sections of culverts such as I have herein described, and further, that with the use of my improved 25 form of connection upon culverts of this design or type, the sections thereof will be prevented from having any detrimental movement with relation to each other such 30 as might detract from the practicability of the same or prevent full accomplishment of the objects sought to be arrived at thereby.

Manifestly, the construction shown is 35 capable of considerable modification, and such modification as is within the scope of my claims I consider within the spirit of my invention.

I claim:

40 1. A connection of the character described comprising a receiving member, and an engaging member adapted for connection with said receiving member having one portion thereof bent laterally into substantially 45 U-shaped fashion and the free end thereof provided with a downwardly disposed lip, the end of which approaches that portion of the engaging member adjacent the point of bending of the laterally U-shaped portion 50 therefrom.

2. A connection of the character described comprising a receiving member, and an engaging member adapted for connection with said receiving member consisting of a single piece of material having a shank por-

tion and a laterally disposed U-shaped upper portion, and a downwardly disposed lip having its free end normally arranged in proximity to the point of bending of said lateral portion from the shank. 60

3. A connection of the character described comprising an eyelet, an engaging member adapted for engagement through said eyelet and consisting of a shank and a laterally opening hook on the upper portion of said shank, and a downwardly disposed lip pivoted to the free end of said hook, the free end of which engages the lower side of said hook with the shank. 65

4. A connection of the character described comprising an eyelet, an engaging member adapted for connection with said eyelet consisting of a shank and a laterally opening offset U-shaped hook portion on said shank having the upper side thereof curved upon 70 itself and a downwardly disposed lip pivoted to the free end of said hooked portion, the end of which engages the lower portion of the hook portion, said lip being of a width 75 corresponding to the opening of said eyelet. 80

5. A connection of the character described comprising an eyelet, an engaging member adapted for connection with said eyelet consisting of a shank portion and a laterally opening hook on the upper portion of said shank, and inwardly swinging means 85 arranged on the free end of the hook adapted to permit engagement of the upper side of said hook through the eyelet but to prevent disengagement thereof with said eyelet when moved in an opposite direction. 90

6. A connection of the character described comprising an eyelet, an engaging member adapted for connection with said eyelet consisting of a single piece of material having a shank portion and a laterally disposed U-shaped upper portion, a downwardly swinging lip pivoted to the upper side of said U-shaped portion, said lip being of a 95 width to permit its passage through the eyelet, but of a length to abut against the lower side of the U-shaped portion whereby to prevent outward swinging movement of the same subsequent to engagement of the 100 hook through the eyelet. 105

In testimony whereof I affix my signature.

HARRY K. SWEENEY.
